UNITED STATES PATENT OFFICE.

JAMES PILKINGTON, OF LIVERPOOL, ENGLAND.

DESIGN FOR A PIPE-CLEANER.

SPECIFICATION forming part of Design No. 29,191, dated August 9, 1898.

Application filed May 13, 1898. Serial No. 680,645. Term of patent 7 years.

To all whom it may concern:

Be it known that I, JAMES PILKINGTON, a subject of the Queen of Great Britain, residing at Liverpool, in the county of Lancaster, England, have invented and produced a new and original Design for a Pipe-Cleaner, of which the following is a specification, reference being had to the accompanying drawing, which illustrates in perspective a pipe-cleaner embodying my design.

The leading feature of my design is the blade or wire A, in width or diameter something less than the bore of the pipe. At the end of this blade is a little tip C, placed eccentrically, and in the center of this tip is a hole c, opening close to the blade. As the small hole in the tip corresponds practically with the hole in the mouthpiece of the pipe, the

tip, which is of slightly less diameter than the mouthpiece, forms no impediment in smoking, but, on the other hand, prevents either nicotine or small bits of tobacco from entering the mouth. The blade or wire has a bend in it, as shown.

Having thus described my invention, I claim—

The design of pipe-cleaner substantially as herein shown and described.

In witness whereof I have hereunto signed my name, this 18th day of April, 1898, in the presence of two subscribing witnesses.

JAMES PILKINGTON.

Witnesses:

G. C. DYMOND,
W. H. BEESTON.
